Primary Examiner—Nelson C. Holtie*Assistant Examiner*—Martha Thompson*Attorney, Agent, or Firm*—Gary L. Griswold; Walter N. Kirn; William L. Huebsch[57] **CLAIM**

The ornamental design for a dispenser for adhesive-backed sheets, as shown and described.

DESCRIPTION

FIG. 1 is a top, right front perspective view of a dispenser for adhesive-backed sheets showing our new design;

FIG. 2 is a rear elevational view thereof;

FIG. 3 is a bottom plan view thereof;

FIG. 4 is a top plan view thereof;

FIG. 5 is a left side elevational view thereof, the right side elevational view being the mirror image thereof; and,

FIG. 6 is a front elevational view thereof.
